UNITED STATES PATENT OFFICE.

AUGUSTUS S. CRANE, OF NEWARK, NEW JERSEY.

ACTUATING DEVICE FOR SECONDARY ELECTRIC CLOCKS.

SPECIFICATION forming part of Letters Patent No. 288,623, dated November 20, 1883.

Application filed May 9, 1883. (No model.)

To all whom it may concern:

Be it known that I, AUGUSTUS S. CRANE, a citizen of the United States, residing at Newark, in the county of Essex and State of New Jersey, have invented certain Improvements in Electric Clocks, of which the following is a specification.

My invention relates, principally, to secondary electric clocks, or those which are driven 10 by an electro-magnet arranged in a circuit which is controlled by a circuit-breaking primary clock; but it is in part applicable to primary clocks, or, indeed, to any analogous apparatus where the successive excitations of one 15 or more electro-magnets are desired to intermittently advance an indicating mechanism.

Figure 1 of the accompanying drawings is a rear elevation of the movement of a secondary electric clock constructed according to the 20 preferred form of my invention. Fig. 2 is a side elevation of the same. Fig. 3 is a fragmentary detail view on a larger scale. Fig. 4 illustrates a modification. Fig. 5 shows a further modification, illustrating the application 25 of my invention to a primary electric clock. Fig. 6 is an enlarged fragmentary view, illustrating another modification, and Fig. 7 is a side view thereof, partially in section.

I will first describe my invention in its application to secondary electric clocks, as illustrated in Figs. 1, 2, and 3.

Let Δ designate the frame of the clock-movement; a , the minute-arbor; b , the tubular hour-arbor; c , the pinion on a ; d , the gear 35 on b ; and e and f , the dial-wheels gearing with c and d , for communicating a reduced motion to the hour-arbor b . These parts are or may be all of the usual construction.

On the arbor a is fixed a wheel, B , having 40 sixty radial teeth, $g g$, on its periphery, equally spaced, forming thereby sixty intervening notches or sockets, $h h$.

C is an anchor which is fixed to and vibrates with the armature D of an electro-magnet, E , and bears two pallets, $i i$, which are fastened to or formed on it at or near its upper end. These pallets are of peculiar form, as best shown in Fig. 3. Each has an inclined 45 propelling-face, j , and two opposite parallel faces, $k k$. While the mechanism is at rest 50 one or other of the pallets is in engagement

with the wheel B , being inserted into one of its notches h , with its parallel faces $k k$ in contact with the two adjoining teeth $g g$. As the faces $k k$ of the pallet are approximately at right angles to the direction of motion of the teeth $g g$, and approximately parallel with the direction of motion of the pallets, the wheel B cannot be turned or displaced until the pallet is withdrawn. Thus a pallet of my construction 55 constitutes a locking-pallet which effectively prevents any accidental displacement of the wheel, and greatly reduces the liability of its being tampered with. Upon the vibration of the anchor C to the opposite side the pallet 60 which has been holding the wheel passes out and frees itself, and simultaneously the opposite pallet engages one of the teeth g , between which the first pallet has been standing, and its inclined face j forces this tooth upward 65 until it passes above that face, whereupon the pallet passes between this tooth and the one below, and the wheel is again locked by the faces $k k$. The motion of the pallets and anchor in each direction is limited by shoulders 70 $l l$, which strike the teeth $g g$, or it may be limited by suitable stops elsewhere arranged; but there must be sufficient motion to cause the faces $k k$ to enter between the teeth $g g$.

The armature is retracted by a spring, m . 80 Its fulcrum-pivots $n n$ are arranged at its ends, so that its pivotal axis traverses it longitudinally along one side or edge, somewhat close to the cores of the magnet. This arrangement admits of bringing the entire armature down 85 over the poles of the magnet, where the attractive power is great, the magnet being necessarily arranged flatwise against the frame Δ , as shown, for the sake of compactness. This arrangement of the armature is made possible 90 by constructing the anchor to work across the edge of the toothed wheel, instead of in the same plane as the wheel. The latter arrangement is that heretofore used in "propelling-escapements," as exemplified in my application for patent filed January 26, 1883, 95 where the two pallets are on diametrically-opposite sides of the wheel, and work alternately toward and from its axis. Even if the pallets in my present construction had no locking faces, they would still possess this advantage of permitting a more effective ar-

angement of the armature, and also the additional important advantage that less accuracy would be necessary in cutting the teeth of the wheel B, as both pallets engage the teeth 5 on the same side of the wheel, so that a slight error in spacing will not affect the operation. In the construction above referred to, however, where the pallets span the wheel and engage it upon diametrically-opposite sides, any 10 error in spacing is doubled in its effect on the operation, so that the successive advances of the wheel exhibit twice the irregularity that there is in the spacing of the teeth.

A secondary clock, constructed as already 15 described with reference to Figs. 1, 2, and 3, being arranged behind a dial and fitted with hour and minute hands, is operated by closing and breaking the line-circuit once each minute, either by leaving the circuit closed for 20 but an instant, in which case the minute-hand will advance a minute on the dial in two quick successive movements, or by closing the circuit once each minute and leaving it closed during thirty seconds, in which case the minute-hand will advance a half-space each half-minute. For the former method it might answer 25 if only one of the pallets were a locking-pallet, the one which acts upon the closure of the circuit having only the inclined face *j*.

30 Fig. 4 shows a different arrangement of magnet and armature and a different construction of wheel B. As the anchor, thus arranged, plays across the face instead of across the edge of the wheel, it is necessary that the teeth *g g* shall project perpendicularly from the face of 35 the wheel. For this purpose the teeth may be formed by short round pins or studs, set in the wheel, as shown, or they may be formed as in Fig. 1, and bent at right angles.

40 Instead of teeth, holes may be used, as shown in Figs. 6 and 7, where *h h* denote round holes punched or drilled through the wheel B, and corresponding to the notches or spaces *h h* in Figs. 1 and 3, while the intervening portions of metal answer to the teeth *g g*. The pallets *i i* are here made of round wire or rod having beveled ends.

Fig. 5 illustrates the application of my 45 present invention to the form of primary electric clock shown in my application for patent filed January 26, 1883, in lieu of the device shown in Fig. 6 thereof. E and E' are the two oppositely-acting electro-magnets, and the toothed wheel B is mounted on the seconds-arbor and has thirty teeth. At the end of each 55 second the current is shunted out of one magnet and into the other, thereby rocking the lever F, vibrating the anchor C to the opposite side, and turning the wheel B one-sixtieth of 60 a revolution.

It is evident that instead of mounting a 65 clock-hand on the arbor *a*, a disk or drum having figures, words, or other characters on its surface or periphery might be mounted upon it or driven from it in such manner as to expose one character at a time through an

opening in a screen. In such case the wheel B might have any required number of teeth other than sixty or thirty.

I am well aware that pendulum-clocks have 70 been provided with escapements somewhat resembling my present invention, in that the pallets have had parallel faces which, if they entered between the teeth on the scape-wheel and remained there, might serve as "locking-pallets" in the same sense as mine. But in all such clocks the vibration of the anchor has been too limited to permit these parallel faces to enter between the teeth; and, moreover, in a pendulum-clock there is no occasion for locking the wheel, since the impulse of the spring 75 keeps the latter in place against the pallets, and, indeed, causes it to communicate motion to the anchor and pendulum.

I am aware, also, of an electric pendulum-clock wherein the pendulum is kept swinging by an electro-magnetic impulse, and is connected to an anchor which it vibrates, and so propels a toothed wheel; but in this clock the pallets enter between the teeth on the wheel 80 only far enough to propel the wheel the requisite distance, and not far enough to interpose locking-faces; nor would it be desirable to do so in a clock of that character, as the pallet no sooner enters the teeth than it recedes. My invention is especially designed 85 for clocks wherein there is a rest between the impulses of sufficient duration to create a liability that the wheel may become displaced sufficiently to derange the operation.

I claim as my invention—

1. As a means for operating an electric clock or other analogous device, the combination, with a wheel having circumferential teeth or sockets, of a vibrating anchor bearing opposed 105 pallets which are formed with inclined propelling-faces, and arranged both on one side of the axis of rotation of the wheel, whereby, when the anchor is vibrated, they alternately engage adjoining or adjacent teeth or sockets 110 for the purpose and to the effect specified, and an electro-magnet connected to and adapted to vibrate said anchor, substantially as set forth, whereby, when said anchor is vibrated in either direction by said magnet, one of said 115 pallets enters a socket or space between two teeth on said wheel, and advances the wheel the distance from one tooth or space to the next.

2. In an electric clock or analogous device, 120 the combination, with a wheel having circumferential teeth or sockets, of a vibrating anchor bearing opposed pallets which are formed with inclined propelling-faces, and one or both of which are formed with locking-faces extending substantially parallel to each other and to the direction of motion of the pallets, and means for vibrating said anchor, all combined and adapted to operate substantially as set forth, whereby whenever the anchor is vibrated in either direction, one of the pallets 125 enters between two teeth on the wheel and 130

propels the latter forward the distance from one tooth to the next, and continues its movement until its parallel locking-faces enter between the two teeth, whereby the wheel is 5 locked or fastened in position until the next vibration of the anchor.

3. In an electric clock or other analogous device, the combination of wheel B, having circumferential teeth or sockets, with anchor 10 C, pallets *i i* thereon, formed with inclined pro-
pelling-face *j*, and one or both formed with op-
posite parallel locking-faces *k k*, extending
substantially parallel with the direction of
motion of the pallets, and approximately at
15 right angles to the direction of motion of the

teeth on the wheel B, and electro-magnet E, the movable portion or armature of which is connected to said anchor and constructed to vibrate the same to a sufficient extent to cause the locking-faces on either pallet to enter between two teeth on the wheel, substantially as set forth. 20

In witness whereof I have hereunto signed my name in the presence of two subscribing witnesses.

AUGUSTUS S. CRANE.
